UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

MACHINE-SWITCHING TELEPHONE SYSTEM.

1,393,502.

Specification of Letters Patent. Patented Oct. 11, 1921.

Application filed December 26, 1917. Serial No. 208,844.

To all whom it may concern:

Be it known that I, HENRY PETER CLAUSEN, a citizen of the United States, residing at Mount Vernon, in the county of 5 Westchester, State of New York, have invented certain new and useful Improvements in Machine-Switching Telephone Systems, of which the following is a full, clear, concise, and exact description.

10 This invention relates to machine switching telephone systems, its object being to effect certain operating refinements and improvements whereby an established connection may be more closely supervised by the 15 parties to the connection.

More particularly the object is to provide means controllable by either the called or calling party to signal the other when the other, either through a misunderstanding or 20 otherwise, has prematurely replaced his receiver on its hook.

A feature of this invention is a means to bring about the desired result. This means is arranged to be responsive to the rapid 25 movements of a subscriber's switchhook so that the operation of recalling the other subscriber in this system simulates the operation of attracting the operator's attention in any well-known manual system. Or this 30 means may equally well respond to a manipulation of a subscriber's calling device.

According to another feature, this means is rendered ineffective when both parties have their receivers off their respective 35 hooks so that one party may not maliciously or otherwise cause ringing current to be applied to the other's line.

According to a further feature, ringing current is instantly applied to the called 40 party's line as soon as the automatic apparatus is connected to, tested and found idle as such called line.

The drawings disclose in Figure 1 so much of a complete circuit involved in an 45 established connection between two substations as is necessary to a clear understanding of the invention.

In Fig. 2, the modification of a slow acting arrangement employed in Fig. 1, is dia- 50 grammatically shown.

The subscriber at substation 1 may in any ordinary manner establish connection to the connector switch which forms the main part of Fig. 1. The brushes 2, 3 and 4 of a se- 55 lector switch are then placed on the terminals 5, 6 and 7 of the trunk terminating in

its connecting switch. Thereupon a circuit is established from ground, battery, the right-hand winding of line relay 8, the normal contact of armature 9 of relay 10, lower talking conductor leading to the subscriber's line through the lower normal contact of relay 11, terminal 6, brush 3, to and through the subscriber's apparatus at substation 1, brush 2, terminal 5, upper normal contact 60 of relay 11, upper talking conductor, normal contact of armature 12 of relay 10, the left-hand winding of relay 8 to ground. Through this circuit relay 8 is energized, and being of the type known as a quick relay, 65 will respond to the manipulation of the subscriber's calling device. At each opening of the circuit just traced, relay 8 will 70 actuate its armatures.

Upon the first energization of relay 8, a 75 circuit is established from ground, the right-hand armature and alternate contact of relay 8, winding of relay 13 to battery and ground.

Relay 13 attracts its armatures and by 80 placing ground on the terminal 7, through its left-hand armature and alternate contact, marks the seized trunk as busy.

When the subscriber at substation 1 ma- 85 nipulates his dial, each break of the line circuit of relay 8 establishes a circuit from ground, right-hand armature and normal contact of relay 8, right-hand armature and contact of relay 13, normal contact of armature 14 of relay 15, winding of relay 16, 90 winding of primary magnet 17, first position contact and side-switch arm 18 to battery and ground. Through this circuit, relay 16 and magnet 17 are energized. Mag- 95 net 17 responds to each separate break in the subscriber's line and relay 16 holds over until the series of impulses has ceased.

The energization of magnet 17 drives 100 brushes 19, 20 and 21 in a primary direction in any well-known manner. Relay 16 in at- tracting its armatures energizes the escapement magnet 22, through its right-hand armature and alternate contact. At the end of the series of impulses, which serve to move the brushes 19, 20 and 21 in the pri- 105 mary direction a requisite number of steps, relay 16 after a short interval becomes de-energized and in turn the escapement mag- net 22 becomes deenergized. In response to this deenergization the side-switch wipers 110 are moved into their second positions.

Thereupon the calling subscriber may now

send the last series of impulses which will cause current to flow through a circuit from ground, right-hand armature and normal contact of relay 8, right-hand armature and 5 contact of relay 13, normal contact of armature 14 of relay 15, relay 16, left-hand armature and contact of relay 23, secondary magnet 24, second position contact and side-switch arm 18 to battery and ground. Secondary magnet 24 responds to these impulses of current in the same manner as the primary magnet 17. In this case, however, the brushes 19, 20 and 21 are moved in a 10 secondary direction and directly set on 15 the terminals of the called party's line.

Should this line prove to be busy, ground will be found on the terminal 25, leading from ground, third position contact and side-switch wiper 26 of another connector switch, 20 brush 21 of this other connector switch, a multiple of terminal 25, thence to brush 21, side-switch wiper 26 and its second position contact, normal contact of armature 27 of relay 23, right-hand winding of relay 23, 25 normal contact of the right-hand armature of relay 16 (when relay 16 becomes de-energized after the second series of impulses), winding of escapement magnet 22 to battery and ground. Through this circuit 30 the escapement magnet 22 is held in an energizing position and the side-switch wipers are not allowed to move into their third positions. Also a source of busy tone current is connected to the calling subscriber's 35 line from transformer 28, contact and inner right-hand armature of relay 23, lower limb of the talking conductors, left-hand winding of relay 10 to battery and ground, whereby through the inductive action of the two 40 windings, this tone is transmitted to the calling subscriber's line in the well-known manner.

If on the other hand the called subscriber's line is idle, terminal 25 will be found to be 45 ungrounded and the escapement magnet 22 will not be held up in the manner described. Therefore, upon its de-energization, the side-switch wipers will be moved into their third 50 positions and relay 15 will be energized through a circuit leading from ground, third position contact and side-switch wiper 26, relay 15, third position contact and side-switch wiper 18 to battery and ground. It should be noted here that the escapement 55 magnet 22 is arranged to move the side-switch wipers into their third position immediately after the relay 16 becomes de-energized. During the energization of relay 16, a circuit is established from ground, left-hand armature and contact of relay 16, relay 60 29 to battery and ground, which relay being slow to release will hold its armatures in their attracted positions for a short interval after the side-switch wipers have been 65 moved into their third position and the re-

lay 15 has been energized as described. Therefore immediately that the called subscriber's line is seized, a ringing current is transmitted from a source of ringing current 30, the alternate contact and lower armature of relay 29, the innermost lower armature and contact of relay 15, brush 20, terminal 30 to and through the bell circuit of the called subscriber's line, terminal 31, brush 19, the contact and upper armature of 70 relay 15, the upper armature and alternate contact of relay 29 to ground. The energizing circuit for relay 29, however, is not maintained, so that after a short interval it retracts its armature, whereupon a source 75 of intermittent ringing current is connected to the called subscriber's line. This source of intermittent ringing current is here shown as a ringing current generator 32 connected to the alternate contact and ground 80 connected to the normal contact of relay 33 intermittently energized through a circuit in which is included an interrupter 34. This source of intermittent ringing current is then connected to the innermost lower armature 85 of a relay 35, thence through the normal contact and lower armature of relay 29 over the circuit previously described, to the upper armature and normal contact of relay 29, the upper armature and normal contact 90 of relay 35, the upper winding of relay 35 of 95 battery and ground.

Through this circuit the ringing of the called subscriber's bell is intermittently continued. When the called subscriber, in answering the summons of his bell, removes his receiver from its hook, the flow of current just described is so increased that the relay 35 will attract its armatures, thereby cutting off this flow of current and substituting therefor a flow of talking current from the windings of relay 10. The attraction of its armatures by relay 35 establishes a locking circuit from ground, battery, lower winding of relay 35, alternate contact and 105 lowermost armature of relay 35, primary off-normal contact 36 to ground.

Talking current is now supplied from ground primary off-normal contact 36, through the lowermost armature and contact 110 of relay 35, the right-hand winding of relay 10, the alternate contact and upper armature of relay 35, thence over the circuit previously described to the innermost lower armature of relay 35 and its alternate contact, 115 left-hand winding of relay 10 to battery and ground. Relay 10 in attracting its armature interposes a break in the circuit of the release magnet 37 and at the same time reverses the flow of current in the calling subscriber's line in the well-known manner.

The release of this switch depends upon the combined action of the calling and called subscribers. When both have hung up their receivers and relays 8 and 10 have both 120

become deenergized, a circuit is established from ground, left-hand armature and normal contact of relay 13, right-hand armature and normal contact of relay 39, primary off normal contact 43, the right-hand armature and normal contact of relay 10, winding of release magnet 37 to battery and ground.

Should the calling subscriber replace his receiver on its hook before the called subscriber was actually through the conversation and should the called subscriber wish to recall him, it may be done through the rapid manipulation of the switchhook at 15 the called subscriber's station 44. The rapid manipulation of the switchhook at this point will cause the armatures of relay 10 to vibrate. As long as relay 10 is in an energizing position, a circuit will be established 20 from ground, contact and armature 45 of relay 10, winding of relay 38 to battery and ground. Through its inner left-hand armature relay 38 completes a circuit through the winding of relay 39, which in turn attracts 25 its armatures. Upon the first break in the called subscriber's line relay 10 momentarily retracts its armature, thereby opening the energizing circuit of relay 38. It retracts its armatures and thereby a circuit 30 is established from ground, through the innermost left-hand armature and normal contact of relay 38, the left-hand armature of relay 39 (which being slow to release holds its armature attracted), and thence 35 through the winding of relay 40 to battery and ground. Following this action relay 10 attracts its armature and a circuit for the energization of relay 38 is reestablished. Thereupon relay 41 is energized through a 40 circuit extending from ground, outermost armature of relay 38, armature and contact of relay 40 to the winding of relay 41 to battery and ground. Upon the second break in the called subscriber's line, the relay 38 45 is deenergized momentarily, whereby a circuit is established from ground, the outer left-hand armature and normal contact of relay 38 through the armature and contact of relay 41, the winding of relay 42 to battery and ground. Upon the attraction of 50 its armature, relay 42 completes a circuit from ground, armature 45 and contact of relay 10, the right-hand contact and armature of relay 42, right-hand contact and armature of relay 38, the outermost left-hand armature of relay 8, which is deenergized, the winding of relay 11 to battery and ground. As long as the subscriber at station 44 rapidly manipulates his switchhook, 55 the movement of the left-hand armatures of relay 38 will maintain the relays 39, 40, 41, and 42 energized and in turn the relay 11 will remain energized.

This will cause ringing current from the generator 46 to flow through the alternate

contact and lower armature of relay 11, terminal 6, brush 3, to and through the bell circuit at the substation 1, brush 2, terminal 5, upper armature and alternate contact of relay 11 to ground.

It will be noticed that, in a similar manner, the subscriber at substation 1 may cause the relay 29 to become energized should the called subscriber prematurely hang up his receiver. If, in answer to the first summons 75 sent, the subscriber does not answer, the calling subscriber may cause the relay 29 to again become energized by actuating his switchhook.

It should also be noticed that, after a connection is established, should either subscriber attempt to cause the flow of ringing current in the other subscriber's instrument, he will fail, for as long as the subscriber toward whom this action is directed 80 has his receiver off the hook, the circuit of the ringing relay associated with his end of the line will be disconnected at the outermost left-hand armature of his supervisory relay.

Fig. 2 represents a modification of the slow acting mechanism represented by the train of relays 38 to 42 inclusive. Relay 10' corresponds to relay 10 of Fig. 1 and relay 8' corresponds to relay 8 of Fig. 1. There 95 is this difference in the construction, however, that the innermost armature and contacts are arranged so that ground is transmitted to the winding of a slow acting magnet 38' only during the movement of said 100 armatures. Being of the make-before-break type, this ground is connected only while the armature is in transit. Thus the manipulation of a subscriber's switchhook will cause a series of impulses from ground, the contacts of either supervisory relay, the winding of slow acting magnet 38' to battery and ground. Upon the first impulse, this magnet so moves its plunger 50 that the contact 51, which corresponds to the right-hand armature and contact of relay 39, is opened. If a train of several impulses is sent to the winding of magnet 38' in the manner described, the roller 52 associated 110 with the plunger 50 will come in contact with the lever 53 and moving upwardly will displace the lever 53 toward the right. Upon the outer movement of the plunger 50 in response to the cessation of impulses, the roller 52 coming in contact with the upper side of the bent portion of lever 53 will cause it to be displaced to the left, whereupon a circuit is established from ground, the contact 54, the lever 53, and thence to the outermost 115 left-hand armature of that supervisory relay controlled by the subscriber who has prematurely hung up, and in the manner previously described either the relay 11 or 120 29 will be energized and the subscriber recalled.

What is claimed is:

1. In a telephone system, telephone lines, a call bell associated with each of said lines, selective switches controlled by a calling subscriber for establishing connections between said lines, and means under control of either of two lines involved in a connection for operating the call bell of the other.
2. In a telephone system, telephone lines, a call bell associated with each of said lines, selective switches for establishing connections between said lines, means for operating the call bell of a called line, and means under control of either a calling or called line for operating the call bell of a calling or called line.
3. In a telephone system, telephone lines, selective switches controlled by a calling subscriber for establishing connections between said lines, means for instantaneously signaling the called line upon the establishment of a connection, means for resignaling the called line before disestablishing the connection, and means for signaling the calling line before the disestablishment of the connection.
4. In a telephone system, a calling line, a called line, a call bell associated with each of said lines, electrically operated means for establishing a connection therebetween, means for operating the call bell of said called line upon the establishment of such connection, means under control of said calling line for subsequently operating the call bell of said called line, and means under control of said called line for operating the call bell of said calling line.
5. In a telephone system, a calling line, a called line, subscriber controlled means for establishing a connection therebetween, means for signaling said called line upon the establishment of such connection, means under control of said calling line for resignaling said called line, means under control of said called line for signaling said calling line, and means under control of the signaled line for disabling said signaling means.
6. In a telephone system, a calling line, a called line, electrically operated switching devices for establishing a connection therebetween, means for instantaneously signaling said called line upon the establishment of such connection, means under control of said calling line for resignaling said called line, and means under control of said called line for signaling said calling line.
7. In a telephone system, the combination of telephone lines, a call bell associated with each of said lines, switching means for interconnecting said lines and a source of signaling current for actuating said call bells, of a slow releasing relay included in said switching means for controlling the application of said signaling current to said lines,
8. In a telephone system, the combination of telephone lines, a call bell associated with each of said lines, switching means for interconnecting said lines and a source of signaling current for actuating said call bells, of a slow releasing relay included in said switching means for controlling the application of said signaling current to said lines, a circuit for the transient energization of said relay incident to the establishment of a connection, means under control of a calling line for thereafter reestablishing said circuit.
9. In a telephone system, a combination of telephone lines, a call bell associated with each of said lines, a connector switch in which said lines terminate, means for setting said connector switch on said lines, and a source of signaling current for actuating said call bells, of a relay for controlling the application of said signaling current to the line upon which said switch has been set, of a second relay for controlling the application of said signaling current to the line under the control of which said switch has been set, means under control of said calling line for energizing said first relay, and means under control of the called line for energizing the said second relay.
10. In a telephone system, a calling line, a called line, means for interconnecting said lines, means under control of either of said lines when interconnected for signaling the other, said signaling means including a slow acting mechanism responsive to a series of impulses created in either of said lines.
11. In a telephone exchange system, a calling line, a called line, means for interconnecting said lines including means for signaling said called line incident to the establishment of a connection between said lines, and a slow acting mechanism responsive to a series of impulses created in either of said lines for signaling the other.
12. In a telephone exchange system, a calling line, a called line, means for interconnecting said lines including means for signaling said called line incident to the establishment of a connection between said lines, a slow acting mechanism responsive to a series of impulses created in either of said lines for signaling the other, and means for nullifying the effect of said mechanism.

In witness whereof, I hereunto subscribe my name this 18th day of December, A. D. 1917.

HENRY P. CLAUSEN.
